TUBING INSERTION AND PULLING
ORGANIZATION FOR DEEP WELLS

Walter C. Sibble, Wellsville, N. Y.

Application May 26, 1941, Serial No. 395,244

4 Claims. (CL 24—263)

This invention relates to a novel and improved tubing insertion and pulling organization for the tubing of deep-well pumps, such as are commonly used in the pumping of oil wells.

Heretofore in the removing or installing of tubing in oil wells besides the regular attendant whose duty in removing is to lift and disconnect the uppermost tubing section from the connecting sleeve or collar it has also been necessary for another attendant provided with a particular and expensive wrench to grip and hold the connecting sleeve or collar during the disconnecting operation and it is one of the objects of this invention to provide a combination of parts, namely, a combined base and cradle member with a tubing-engaging and tongs-organization for removable seating in the cradle member in such manner as to prevent a rotation of the coupling sleeve or collar between adjacent tubing sections thereby avoiding the necessity of the second attendant and the expensive wrench.

More particularly the invention consists in the provision of a device of the above mentioned character in which upwardly projecting and laterally spaced members are provided on each side of the base portion of the combined base and cradle member which are provided in turn with downwardly converging faces for co-operating with complementary surfaces on the tubing-engaging and tongs-organization to cause a gripping of the connecting sleeve by the latter organization when seated in the cradle member.

It is an additional and equally important object of the present invention to provide a device of the above mentioned character in which the tubing-engaging and tongs-organization includes a pair of pivoted jaw-like members adapted to be removably clamped together about the tubing and provided with sleeve or collar receiving means and gripping means which latter are forced into gripping engagement with the coupling sleeve when the organization is seated in the cradle.

Other objects as well as the nature, characteristic features and scope of the invention will be more readily apparent from the following description taken in connection with the accompanying drawings and pointed out in the claims forming a part of this invention.

The invention is clearly illustrated in the accompanying drawings, in which—

Fig. 1 is an end view of the combined base and cradle member,

Fig. 2 is a top plan view thereof,

Fig. 3 is an end elevational detail showing the

tubing-engaging and tongs-organization seated in the cradle member,

Fig. 4 is another end elevational view looking toward the opposite end of the same arrangement of parts,

Fig. 5 is a top plan view of the complete device in assembled relation,

Fig. 6 is a side elevational view of the arrangement shown in Fig. 5,

Fig. 7 is a vertical cross sectional view taken on line 7—7 of Fig. 5 in the direction in which the arrow points, and

Fig. 8 is an elevational view looking toward the inside of one of the jaws of the tubing-engaging and tongs-organization.

Similar characters of reference are employed in all of the above described views to indicate corresponding parts.

Referring now, more particularly, to the accompanying drawings there is provided a combined base and cradle member generally designated 1 and including a base portion 2, the ends of which are slotted as at 3 and adapted to receive suitable nut and bolt arrangements not shown for fastening the base portion to the top of the well casing c in such manner that the opening 3' will be positioned centrally of the casing for the passage of well tubing therethrough. A plurality of pairs of upwardly projecting laterally spaced members 25 4 are provided on the upper surface of said base portion 2, the inner opposing faces of said spaced members converging downwardly as shown at 5 for coacting with each other in removably receiving the improved tubing-engaging and tongs-organization generally designated 6.

The tongs-organization or tongs may be said to consist of a pair of jaw members 7 the inner ends of which are in loosely hinged engagement with each other as indicated at 8 while the inner faces are provided with opposed semi-circular recesses 9, the upper portions 10 of which are enlarged to leave the shoulders 11. When in substantially closed relation the lower portions of the recesses 9 form an opening for arrangement 40 about a tube section 12 while the upper portions 10 are disposed on opposite sides of a connecting sleeve 13 forming a part of the tubing, the lower edge of the sleeve being adapted to be seated on the shoulders 11 and thereby acting as a support 45 to prevent the accidental dropping of the entire tubing into the well.

The inner surfaces of the enlarged recessed portions are removably fitted with bits 14 as clearly shown in Figs. 5 and 7 and diagonally opposed bits co-operate with each other when

engaged with the sleeve 13 for preventing rotation of the sleeve in one direction while the remaining diagonally opposed bits co-operate with each other in preventing rotation of the coupling sleeve in a reverse direction, this biting engagement being effected when the opposed downwardly converging outer faces 15 of the jaws are seated on the corresponding complementary downwardly converging faces 5 of the members 4.

The jaws are provided with handles 16 so that they may be readily manipulated while suitable latching means is provided for holding the jaws in closed position. In the present instance the latching means may be said to consist of a bolt 17 fitted with a handle 18, the bolt being arranged through transverse apertures in the handles, the outer end of the bolt 17 being formed with a reduced and flattened head 19 which forms a substantial T relative to the shank and which is adapted to be passed through either pair of crossed slots 20 which intersect the adjacent opening and which enable the T-head to be passed through the slots and the bolt subsequently turned a fractional degree so as to engage on the outer surface of the adjacent handle member and thereby latch the same in position, the arrangement being clearly illustrated in Figs. 5 and 6 of the drawings, the dotted lines in Fig. 6 showing the angular position which may be assumed by the handle 18 to effect registration of the head 19 of the bolt with the desired slot 20.

Arranged on opposite portions of the outer surfaces of the jaws between the inclined portions 15 are ears 21 in which bails 22 are pivotally mounted, the latter after the parts are arranged as shown in Fig. 7 being adapted to be swung upwardly and engaged by a hook 23 which is adapted in turn to be connected with a pulling cable not shown forming in turn a part of the power driven lifting mechanism of the conventional oil well equipment. In use the base 1 is seated upon the upper part of the well casing c as shown in Figs. 6 and 7. The jaws 7 of the tongs-organization are then moved toward each other about an elevated portion of the tubing and beneath the adjacent connecting sleeve 13 so that the latter is seated on the shoulders. On being latched together the jaws are position so that their inclined surfaces 15 are engaged with the inclined or converging faces 5 of the cradle member and owing to these converging surfaces the jaws are drawn toward each other and the bits 14 automatically forced into biting engagement with the sleeve. Bails 22 are swung upwardly and engaged with the hook 23 of the lifting means and the tongs-organization lifted until the next succeeding connecting sleeve is drawn into a position above the cradle and engaged by another tongs-organization. In all instances the upper part of the coupling sleeve is held while the upper projecting section of the tubing not shown may be disengaged from the upper part of the sleeve by the single attendant. Obviously the reverse operation is repeated when it is desired to re-install the tubing.

In Fig. 8 there is shown a slightly modified form of bit structure consisting in employing two small bits 14' in lieu of one.

It is believed in view of the foregoing that a further detailed description of the operation of the invention is entirely unnecessary. Likewise it is believed that the advantages of the invention will be readily apparent.

Having thus fully described the invention what is claimed as new and desired to be secured by Letters Patent is:

1. In a pulling organization for the tubing-equipment of deep-well pumps, the combination with a combined base-and-cradle member including a base portion adapted to be seated upon and supported by the upper end of the casing of a well, and a plurality of pairs of upwardly-projecting laterally-spaced members upon each side of said base portion the inner opposing faces of which spaced members converge downwardly, of a tubing-engaging tongs-organization having downwardly converging seating portions removably seated between the opposing faces of said laterally-spaced members, and including coupling sleeve-receiving and coupling sleeve-gripping means and the gripping means being forced into gripping engagement with the coupling sleeve when the organization is seated on the downwardly converging faces of the cradle member.

2. An arrangement as claimed in claim 1, in which the tongs-organization includes a pair of jaws hingedly connected to each other at their inner ends and provided with handles at their outer ends, and latching means for removably holding the handles together.

3. In a pulling organization for the tubing-equipment of deep-well pumps, the combination with a combined base-and-cradle member including a base portion adapted to be seated upon and supported by the upper end of the casing of a well, and a plurality of pairs of upwardly-projecting laterally-spaced members upon each side of said base portion the inner opposing faces of which spaced members converge downwardly, of a pair of jaws operatively connected to each other at their inner ends and adapted to be arranged about a section of tubing and the adjacent coupling sleeve and provided internally with gripping means for engagement with the coupling sleeve, the outer faces of the jaws having spaced downwardly converging seating portions for removable engagement with the opposing faces of said laterally spaced members whereby the gripping means on the jaws are caused to tightly bite the coupling sleeve, handles on the outer ends of the jaws, and latching means for removably holding the handles together.

4. An arrangement as claimed in claim 3, in which balls are pivotally connected to the outer faces of the jaws between the downwardly converging seating portions.

WALTER C. SIBBLE.
